(57) **CLAIM**

The ornamental design for a syringe barrel, as shown and described.

DESCRIPTION

FIG. 1 is a front view of a syringe barrel showing our new design in a first environment;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of a syringe barrel showing our new design in a second environment;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The dash dot lines immediately adjacent to the claimed areas in the views represent the boundaries of the claimed design. The dashed lines in the figures illustrate the portions of the design that form no part of the claimed design. None of the broken lines form any part of the claimed design. This article is transparent except letters and graduations.

1 Claim, 6 Drawing Sheets
